UNITED STATES PATENT OFFICE.

DOUGLAS TURNER, OF ST. LOUIS, MISSOURI, ASSIGNOR TO THE MEASUREGRAPH COMPANY, OF ST. LOUIS, MISSOURI, A CORPORATION OF DELAWARE.

CALCULATING MACHINE.

Application filed January 28, 1920. Serial No. 354,568.

To all whom it may concern:

Be it known that I, DOUGLAS TURNER, a citizen of the United States, residing at St. Louis and State of Missouri, have invented 5 certain new and useful Improvements in Calculating Machines, of which the following is a specification.

This invention relates to calculating machines and its general object is to produce a 10 compact machine of simple construction which will present a relatively large area for carrying the computations. The features of the invention are particularly applicable to that type of machine in which a 15 plurality of indicating members or rollers are carried upon a movable carrier or cage, and one of the objects of my invention is to provide simple key-controlled means for bringing the cage into position to present 20 any one of the indicating members opposite the reading point of the machine, at the same time rotating the indicating member so as to present the proper computation at the reading point, the computations on the 25 indicating members being functions of the numbers carried by the keys. The machine is particularly adapted for performing multiplications and while it has a wide range of usefulness, it is expected to be especially 30 useful in expediting the laborious work of making up payrolls from workmen's time cards, where the workmen have different wage-rates.

In the embodiment shown I have described 35 a pay roll calculating mechanism which is constructed for use with the so-called international time system, in which time is calculated by tenths of hours. The units of payments illustrated in the accompanying drawings run from $17\frac{1}{2}\%$ per hour 40 to $85\frac{1}{2}\%$ per hour by $2\frac{1}{2}\%$ intervals. It will be obvious that such calculations require the multiplication of two figures, one representing 45 the period of time and the other the unit price and it will be understood that my mechanism is adapted to other similar calculations involving one multiplicand and one multiplier.

Further objects of the invention will appear 50 hereinafter.

The invention consists in the novel features, and in the general combination of parts to be particularly described herein- 55 after, all of which contribute to produce

a simple and efficient calculating machine. 55 A preferred embodiment of my invention will be particularly described in the following specification, while the broad scope of my invention will be pointed out in the appended claims. 60

In the drawing, which fully illustrates my invention,

Figure 1 is a plan view of my machine.

Fig. 2 is a side elevation of the same.

Fig. 3 is an enlarged detail of the sight 65 opening and price scale construction.

Fig. 4 is a transverse section along the line 4—4 of Fig. 11.

Fig. 5 is a similar section on the line 5—5 70 of Fig. 11.

Fig. 6 is a similar section on the line 6—6 of Fig. 11.

Fig. 7 is a similar section on the line 7—7 75 of Fig. 11.

Fig. 8 is a transverse section on the line 8—8 of Fig. 11.

Fig. 9 is a section similar to Fig. 7 with the keys in depressed position.

Fig. 10 is a view similar to Fig. 9 showing one of the locking bars in locking engagement 80 with one of the discs.

Fig. 11 is a horizontal section through the center line of the main shaft.

Fig. 12 is an elevation to enlarged scale of one of the indicating rollers or cylinders. 85

Fig. 12^a is a vertical section therethrough.

Fig. 13 is an enlarged detail view of a pair of keys and plunger, one of the former being locked in depressed position.

Fig. 14 is a front elevation of the same. 90

Fig. 15 is a vertical section of the same.

Fig. 16 is a detail of modified price cylinder construction.

Fig. 17 is a plan view of a portion of the time slip holding rack.

Fig. 18 is a detail of one of the rack and pinion mechanisms.

Like numerals refer to like elements throughout the drawings. The machine comprises a base 1 and two banks of keys 100 generally indicated by numeral 2. The case 4 houses the mechanism and is provided with a sight opening permitting a view of the proper indicating cylinder. At the left side of the machine is provided a handle 5 105 in convenient reach of the operator. A vertical board or rack 6 is located above the sight opening 3, the same comprising a plate

7 having the metal strips or cleats 8 secured to the front face thereof, see Fig. 17. These cleats or strips are so located as to accommodate a memo or time slip between each pair, the indicating figures on the indicating cylinders being correspondingly spaced so that, in effect, the space between each pair of cleats will accommodate the time slips of all of the workmen working at a certain rate or memo slips bearing the name or number of each workman working at that rate upon which may be noted the successive indications made as a result of successive calculations over periods of time for which the pay is to be calculated. I have designated by numeral 9, for example, the space between a pair of cleats which is located above the rate of 77½ per hour.

Within the casing are provided a plurality of indicating members in the form of horizontally disposed cylinders or rolls 10 carried in a carrier or cage formed of two spiders or end pieces 11, cored or apertured at 11^a for lightness, see Fig. 5. The spiders 11 are carried by the shaft 12 which is journaled in ball bearings 13 at either end, see Fig. 11, these bearings being carried by suitable vertical frame plates or uprights 14 and 15. Located beneath the shaft 12 is a second horizontal shaft 16 to which is attached the operating handle 5. I have provided mechanism to yieldingly transmit rotation of the shaft 16 to the shaft 12 which consists of a sector or segment 17 having suitable teeth formed upon its periphery. This segment is in mesh with a gear or pinion 19 loosely mounted upon the shaft 12. This pinion is formed with a radial arm 23 provided with a pivotally attached pawl 22 which engages a ratchet wheel 21 rigid with the shaft 12. A spring 24 serves to maintain the pawl 22 in contact with the ratchet 21. The handle 5 is provided with a pin 5^a extending through a slot 15^a in the upright 15. The segment 17 is provided with a pin or stud 17^a, see Fig. 4, and a coiled spring 29 connects the pin 5^a and the pin 17^a. When the handle 5 is moved to the left in the operating stroke, as viewed in Fig. 4, the tension put upon the spring 29 will rotate the segment 17 which will rotate the pinion 19 and radial arm 23. The latter, by virtue of the engagement of its pawl 22, will rotate the ratchet 21 and thereby the shaft 12, the rotation of which will rotate the spiders 11 carrying the indicating cylinders, this movement being for the purpose of alining the proper roller beneath the sight opening 3, as will be more fully described hereinafter.

Adjacent one extremity of the shaft 16 is attached an arm 25 to which is attached one end of a coiled spring 26, the other end thereof being secured to the casing at a suitable point indicated by numeral 27, see Figs.

8 and 11. It will be obvious that rotation of the shaft 16 will be resisted by the spring 26 which will serve to return the shaft and operating handle 5 to normal position. The rollers or cylinders, which carry the price computations or products resulting from the multiplications, are constructed so that they are as light as possible in order to eliminate, so far as possible, movement of the cage due to momentum, at the completion of a setting movement. In the form shown in Figs. 1-15, for example, the cylinders are constructed of light aluminum tubing 30 having heads of steel, or the like, indicated by numerals 31 and 32 in each end thereof. The computations are printed upon thin paper and secured to the cylinders or rolls by any suitable adhesive. The heads 31 and 32 are provided with trunnions journaled in the spiders 11 of the cage, as shown in Fig. 11. Secured to extremities of these trunnions of the heads 31 are gears or pinions 35.

Rotatably mounted on the shaft 12 is a sleeve 33, see Fig. 11, which carries a gear 34 which is in mesh with all of the pinions 35. These gears are so constructed that the ratio between the teeth thereon will be an integer, such ratio being 2, 3, 4, 5, etc., as desired. In other words, a complete rotation of the gear 34 will result in an even number of rotations of the cylinders 10. Secured upon the sleeve 33 is a ratchet 21' (similar to the ratchet 21) see Fig. 8. A radial arm 23', carrying the pawl 22' and a spring 24', is rotatably mounted on the shaft 12 and is formed with or secured to the pinion 20. A segment or sector is provided, consisting of a radial arm 18^a having its toothed and curved portion 18 in mesh with the pinion 20, such sector being rotatably mounted upon the shaft 16. An operating arm 18' is provided, the same lying in back of the sector 18, as viewed in Fig. 8. This arm 18' is also provided with an angularly disposed arm which is secured to the shaft 16 and rotates therewith and is provided with the pin 18'' to which one end of the coiled spring 28 is attached, the other end thereof being secured to a suitable pin 18^b upon the sector 18, see Fig. 8, so that rotation of the shaft 16 in an operating stroke of the handle 5 will move the rack 18 through the medium of spring 28 and thereby rotate the pinion 20, arm 23' and ratchet 21' to rotate the sleeve 33 and gear 34. The purpose of this movement is to transmit rotation in one direction to the cylinders about their individual axes.

I provide key controlled means for positioning the indicating members opposite the reading point, and for controlling their rotation on their axes. This means will now be described. Rigidly attached to the sleeve 33 is a bank or series of notched discs 36

shown as ten in number, each of these discs having the properly located notch 37 in its periphery. A second bank or series of discs 38 is rigidly attached to the shaft 12, these also being ten in number in the form shown and being each provided with a properly located notch.

The key bank consists of two series of ten keys arranged as shown in Fig. 1, for example, one set of keys representing tenths of hours, the other representing hours, each set of keys being numbered from zero to nine inclusive. The hour keys coact with the set of discs 38 while the tenth keys coact with the discs 36. I provide means including parts moving with the cage, and parts moving with the rollers 10, co-operating with the keys to stop the cage and also the rollers in predetermined positions. For this purpose a lock bar 40 extends from beneath each of the tenth keys 2^a, see Fig. 7 for example, and a lock bar 39 extends from beneath each of the hour keys 2^b. Each key is constructed with a head 41, see Figs. 13 and 15, and a shank or plunger 42 slidably mounted in the base 1 and in the horizontal bars 43, see Fig. 13. The lower part of each shank 42 is slotted as indicated by numeral 44, see Fig. 14, to accommodate the end of the coacting lock bar 39 or 40, lock bars 39 being curved or off-set to pass beneath bars 40 without interference, see Fig. 7, for example. A washer 49 is slidably mounted upon each of the shanks 42 and rests upon the end of the coacting locking bar, as shown in Fig. 13. Secured to the shanks 42 are the collars 48 and a coiled spring 50 extends between each washer 49 and the corresponding collar 48. At the upper end of the shanks are provided washers 46 and coiled springs 45 extend therebetween and the bars 43, these springs serving to normally maintain the keys in undepressed position. The locking bars 39 and 40 are pivoted upon the rod 40^a, see Fig. 7.

Placed longitudinally one for each bank of keys 2^a, 2^b are two series of locking pawls 51, each provided with upward engaging ends which, when the keys are depressed, will slip over the collars 48 into engagement therewith, as shown, for example, at the right hand of Fig. 13. Coiled springs 53 coact with each set of locking pawls to normally maintain them in position to engage the collars 48. Since each set of pawls operates as a unit, it would be obvious that, should the wrong key in a horizontal bank be depressed, depression immediately thereafter of the proper key will operate to release the previously depressed key prior to retention in depressed position of the latter depressed key. A longitudinal release bar 54 is provided to release all of the keys simultaneously, the two sets of pawls being operatively connected by a link 55, which is

slotted at 55^a to permit independent actuations of the pawls during calculation operation.

The locking bars 39 and 40 have their outer extremities adjacent the peripheries of the discs 36 and 38 and depression of a key will exert a yielding pressure upon one end of a locking bar to bring its other end into contact with a corresponding disc, which will be permitted to rotate until the notch 75 therein alines itself with the end of the locking bar, the yielding pressure upon which will ensure engagement or entrance of the end of the locking bar into such notch, thereby locking the disc against further 80 movement.

To assist the operator in the determination of his calculations, especially where the majority of the same are made on a basis of one rate, I provide a framing device 60 slidably mounted upon the rod 61 adjacent to the sight opening 3, see Fig. 1, this framing device being so constructed as to embrace the unit rate and the opening therebeneath in which the calculation at that rate is to 90 be located.

In the operation of the machine, assuming, for example, that the time slip shows an employee to have worked 3.8 hours in one day at 30¢ per hour, the key operating the 95 numeral 3 in the hours bank is depressed as is the key bearing the numeral 8 in the tenths bank. Thereafter the handle 5 is pulled toward the operator and the racks 17 and 18 are thereby rotated until the lock bars 39 and 40, corresponding to the depressed hours and tenths keys, engage with their corresponding discs 38 and 36. It will be understood that the notches in the discs are properly located in such manner that 100 rotation of the shafts 12 will be permitted to aline that cylinder beneath the sight opening 3 which corresponds to the numeral depressed in the hours bank and movement of the sleeve 33 will be effected which will 105 rotate such cylinder on its axis through the medium of gears 34 and 35 an amount sufficient to aline the proper set of numerals on such roll or cylinder beneath the sight opening 3. In other words, the indication 110 beneath the sight opening is the result of two movements,—one the rotation of the cage about the axis of shaft 12 to locate the proper cylinder beneath the sight opening and the other the rotation of such cylinder about its own axis an amount sufficient to 115 aline the set of numerals corresponding to the depressed tenths key beneath such opening. Should the relation of the notches and locking bars be such that, for example, the locking bar 39 is engaged with one of the discs 38 prior to the engagement of the actuated locking bar 40 with one of the discs 36, it will be apparent that movement of the 120 shaft 12 will cease, but the operating lever 5 125

130

may continue its operating stroke due to the provision of the spring 29, as will be apparent. In the example given, where numeral key "3" of the hours keys and numeral key 5 "8" of the tenths keys have been depressed, the cylinder representing the third set of figures will move during actuation of the operating handle 5 until alined beneath the opening 3 and such cylinder will be rotated 10 until the set of figures representing 3.8 of an hour thereon are alined at rest beneath the sight opening 3, after which the operator will note the product on the memo slip in the superimposed rack and will proceed 15 to obtain the next calculation.

In the above it will be seen that the first roller or cylinder of the set carries the calculations at from one-tenth of an hour to nine-tenths of an hour, a row of blanks being left representing zero-tenths indication. The second cylinder will bear the calculations for one hour to 1.9 hours and so on.

It is to be noted that with the mechanism described, where calculation for an even hour is to be made, not only is the proper hour key depressed, but the zero key of the tenths set is also depressed. Similarly, where the total for a fraction of an hour is to be obtained, the zero hours key is depressed in addition to the proper tenths key.

It will be obvious that, while I have described and illustrated a machine intended to calculate according to the International time system, the sets of figures may be varied to accord with any requirements where the use of a single multiplier and multiplicand is involved. In Fig. 16, for example, I have illustrated a removable thimble 63 bearing the desired indications, which may be slipped upon the cylinder 63^a, the thimble having the tongue 62 slidable in the groove 63^b to ensure proper positioning of the thimble. This construction permits ready replacement of calculating thimbles, if desired.

It is understood that the embodiment of the invention described herein is only one of the many embodiments my invention may take, and I do not wish to be limited in the practice of my invention nor in my claims, to the particular embodiment set forth.

What I claim is:—

1. A machine of the class described, having a sight opening, a plurality of indicating members, each carrying a series of products thereon, a key-controlled means to position any of said members beneath said opening, and a key-controlled means to position the proper product on said member.

2. A machine of the class described, having a sight opening, a plurality of indicating members, each carrying a series of products thereon, a key-controlled means to position any of said members beneath said opening, a key-controlled means to position

the proper product on said member, and a common actuating means for both of said key-controlled means.

3. In a calculating machine having a reading point at which the calculations may be read, the combination of a movable carrier, a plurality of indicating members bearing computations, and movably mounted on the carrier, key-controlled means to position any of the indicating members at the reading point, and key controlled means to rotate the indicating members to bring the computations in view at the reading point.

4. In a machine of the class described, a plurality of indicating cylinders, a plurality of products on each of said cylinders, means to rotate all of said cylinders about a common axis, means to revolve each of said cylinders about its own axis, key-actuated mechanism to control said first-named movement, and key-actuated mechanism to control said second-named movement of said cylinders.

5. In mechanism of the class described, an indicating cylinder, a rotatable cylinder carrying means, means to revolve said cylinder about its axis, means to control the rotation of said carrying means, said last-named means comprising a disc having a notch, a locking bar having means adapted to engage said notch, actuating means for the locking bar operable to move said bar into yielding engagement with said disc, and means associated therewith for yieldingly pressing the locking bar against the disc.

6. In mechanism of the class described, a plurality of indicating cylinders, a rotatable cylinder carrying means, means to revolve said cylinders about their axes, means to control such revolution, said means comprising disks, locking bars and key actuated means operable to move said locking bars into engagement with said disks, the latter being notched, and said locking bars each having means to engage the notch of a corresponding disk.

7. In a machine of the class described a rotatable shaft, spaced apart cage members carried by said shaft, a plurality of indicating cylinders journalled in said cage members, pinions operatively attached to said cylinders, a rotatable gear in constant mesh with all of said pinions, and key-controlled means for rotating the gear and the cage members.

8. In a machine of the class described, a rotatable shaft, spaced apart cage members carried by said shaft, a plurality of indicating cylinders journalled in said cage members, pinions operatively attached to said cylinders, a rotatable gear in constant mesh with all of said pinions, key-controlled means for stopping the rotation of the cage members and the cylinders in predetermined positions, and manually operated yielding means

for rotating the cage-members and the cylinders.

9. In a machine of the class described a rotatable shaft, spaced apart cage members 5 carried by said shaft, a plurality of indicating cylinders journalled in said cage members, means to rotate said shaft, said means comprising an operating handle, a pinion carried by said shaft, a segment in mesh with said pinion and means to yieldingly connect said operating handle to said segment.

10. In a mechanism of the class described, a rotatable shaft, cage members carried thereby, indicating members journalled therein, means to rotate said shaft, said means comprising a pinion carried by said shaft, a sector-shaped rack in mesh therewith, means to rotate said rack, said means 20 comprising an actuating handle, a shaft, said rack being journalled on said shaft, and means operatively connecting said actuating handle to said rack, said means comprising a coiled spring.

25 11. In a machine of the class described, a rotatable shaft, cage members carried thereby, indicating cylinders journalled in said cage members, pinions carried by said indicating members, a sleeve journalled on said shaft, a gear carried by said sleeve in mesh with said indicating member and pinions, means to rotate said sleeve, said means comprising a second shaft, a sector-shaped rack rotatable thereon, a pinion carried by said 30 sleeve in mesh with said rack, and means to operatively connect said rack to said second-named shaft, said means comprising a coiled spring.

40 12. In a machine of the class described, rotatable cage members, indicating members journalled in said cage members, said indicating members being provided with pinions, a gear in mesh with said pinions, a sleeve carrying said gear, a plurality of discs carried by said sleeve, and a plurality of locking bars coactable, one with each of said discs.

45 13. In a machine of the class described, rotatable cage members, indicating members journalled in said cage members, said indicating members being provided with pinions, a gear in mesh with said pinions, a sleeve carrying said gear, a plurality of discs carried by said sleeve, and a plurality of locking bars coactable, one with each of said 50 discs and means to maintain said bars when actuated in yielding contact with said disks.

55 14. In a machine of the class described, rotatable cage members, a shaft carrying said cage members, indicating cylinders carried by said cage members, means to rotate said shaft, a plurality of discs carried thereby, and a plurality of locking bars coactable with said discs.

60 15. In a machine of the class described,

rotatable cage members, a shaft carrying said cage members, indicating cylinders carried by said cage members, means to rotate said shaft, a plurality of discs carried thereby and a plurality of locking bars coactable 70 with said discs, each of said discs being notched and each of said bars being provided with means to engage a notch in one of said discs.

16. In a machine of the class described, a 75 rotatable disc, a pivoted locking bar, said disc being provided with a notch, said locking bar having a portion engageable with said notch, means to actuate said locking bar, said means comprising a depressible 80 plunger, a washer slidably mounted upon said plunger in engagement with said locking bar, and a spring contacting with said washer and operatively interposed between said plunger and washer to yieldingly press 85 the locking bar against the disc and move the bar into the notch when the same comes opposite to the bar.

17. In mechanism of the class described, a carrying member, a plurality of indicating 90 cylinders rotatably mounted in said carrying member, a shaft, said carrying member being secured thereto, a common actuating handle, means to transmit rotation thereof to said shaft, gear mechanism to revolve said 95 indicating members about their axes, and means to transmit the rotation of said actuating handle to said gear mechanism.

18. In mechanism of the class described, a shaft, spiders carried thereby to rotate 100 therewith, a plurality of indicating cylinders journalled between said spiders, means to revolve said indicating members about their individual axes comprising gear and pinion mechanism, a second shaft, an actuating handle secured thereto, yielding means for transmitting the rotation of said second shaft to said first shaft, and yielding means for transmitting the rotation of said second shaft to said gear and pinion mechanism, 105 said yielding means operating to enable either the spiders or the gear and pinion mechanism to be independently stopped.

19. In mechanism of the class described, a rotatable shaft, spiders carried thereby, a 110 plurality of revoluble indicating cylinders journalled between said frame members, means to revolve said indicating members about their individual axes, said means comprising pinions, and a gear in mesh therewith, a sleeve rotatable on said shaft and carrying said gear, means to rotate said shaft, means to independently rotate said sleeve, a second shaft, an actuating handle attached thereto, and means to actuate each of said rotation causing means, said last named means including yieldable elements.

20. In a calculating machine of the kind described, a casing, a rotatable cage mounted therein, a plurality of rotatable indicating 115 120 125 130

rollers bearing computations, and carried by the cage, a set of cage-controlling keys, means controlled by said keys and including means moving with the cage for stopping the same at predetermined positions, a set of roller controlling keys, means controlled by said last named keys and including means moving with the rollers for stopping the

rollers in predetermined positions, a common operating handle, and yielding means actuated thereby for rotating the cage and for rotating the rollers. ¹⁰

In testimony whereof I have subscribed my name.

DOUGLAS TURNER.
